UNITED STATES PATENT OFFICE.

GEORGE M. WILLIS, OF CHICAGO, ILLINOIS.

ALARM AND SIGNALING SYSTEM.

947,208.

Specification of Letters Patent. Patented Jan. 18, 1910.

Application filed May 7, 1906. Serial No. 315,474.

To all whom it may concern:

Be it known that I, GEORGE M. WILLIS, citizen of the United States, residing at Chicago, in the county of Cook and State of Illinois, have invented a certain new and useful Improvement in Alarm and Signaling Systems, of which the following is a full, clear, concise, and exact description, reference being had to the accompanying drawings, forming a part of this specification.

My invention relates to combined watchmen's signaling and fire alarm systems, more particularly to substation apparatus whereby the circuit may be controlled or interrupted to telegraph to a central station the number of the substation according to a predetermined code. In systems of this kind it is desirable to have the substation apparatus of such construction that a watchman, in making his rounds, may operate the substation apparatus in a simple manner in order to make the report of his beat, and it is also desirable that the apparatus may be operated by a citizen, in case of fire, quickly and easily and in a simple manner.

It is the object of this invention to secure these desirable results, and it is also the object to provide apparatus the various parts of which are of simple construction and of such relative disposition that the mechanism will be free from complication and consequent liability of disarrangement.

My invention also provides means whereby the two different signals may be distinguished from one another at the central station.

The various advantages secured by the construction of my invention will be pointed out hereinafter.

My invention will be more clearly understood by reference to the accompanying drawings, in which—

Figure 1 is a perspective view of the substation box; Fig. 2 is an elevation view, parts being removed to reveal the interior mechanism; Fig. 3 is a side elevation of the interior mechanism, the outer casing being shown in section; Figs. 4 and 5 are detail views which will be hereinafter referred to.

The case 1 may be of iron or other suitable material and is provided at 2 with a cover hinged to the case at 3—3. In order that the cover may normally be kept closed, I provide the construction shown in Figs. 1

and 5. Cast integrally with the casing is the bifurcated lug 4 to which is proximate, when the door is closed, the lug 5 which is cast integrally with the cover 2. Pivoted at 6 in the lug 5 is the handle 7 which, when the door is closed, is adapted to be swung into engagement with the slot 8 in the lug 4. The ends of the lug 4 are provided with the openings 9 which are adapted for the reception of a soft metal wire 10 which is shown in Fig. 1, the ends of which may be twisted together and a lump of soft metal 11, for instance, a piece of lead, may be threaded upon the twisted wire and then by means of a clamp or other compressing device may be pressed into any desirable shape whereby the wires may be securely held together.

When it is desired to open the box the handle 7 is swung about the pivot 6 and out of the slot 8 in the lug 4 thereby cutting the soft wire and allowing the release of the cover 2. This kind of connection will admit of the ready opening of the box but forms a seal which may be replaced each time the box is opened and which, therefore, secures the box against tamperers or other persons wishing to open the box for other than fire alarm purposes. The wires may be sealed by a special tool whereby the sealer or authorized officer may be identified. It is evident that this construction eliminates the usual glass front which would necessitate breaking, which is an undesirable construction on account of the danger of cutting one's hand or of the liability of broken glass to interfere with the operating mechanism.

In order that the box may not be closed by any one other than an authorized officer, I provide means such as is shown in Figs. 1, 3 and 4. This construction consists of a cylinder 12 mounted in a partition 13 which is secured to the lugs 14—14 on the case 1 by means of screws 15—15. Mounted to slide within the cylinder 12 is the plunger 13', which is provided with the pin 14' which is adapted to ride within the slot 15' of the cylinder 12. The plunger 13' is also provided with a stem 16 about which is disposed the helical spring 17 which is secured to the cylinder and to the stem and which exerts a torsional and a longitudinal pressure upon the plunger 13'. The plunger 13' is also provided with the extension 18 which, when the door is closed, is adapted to extend

into the aperture 19 in the cover 2. The inner surface of the cover 2 engages the shoulder 19 upon the plunger and normally retains the pin 14' within the slot 15'. 5 When the door is opened the spring 17 will force the plunger outwardly, thereby disengaging the pin 14' from the slot 15', and also, on account of this torsional tendency, will draw the pin 14' away from the slot 10 15', as is shown in Fig. 4, this figure being an elevation view of this portion of the mechanism. It is evident that when the plunger is in this position the door is prevented from being entirely closed. The extension 18 is adapted to be engaged by a key 15 furnished to the authorized officer whereby the plunger 13' may be turned about until the pin 14' is proximate to the slot 15', whereby the door may be closed and locked 20 as has been described.

Referring now to Figs. 2 and 3, I have therein shown the mechanism for controlling the line circuit. To the back wall 20 of the case 1 is secured the slab 21 of slate or other 25 similar material by means of the screws 22-22. Secured to the slab is the base plate 23 upon which are mounted the pillars 24-24. A supporting plate 25 is secured to the pillars 24-24 by means of screws. A 30 main shaft 25' is mounted in the plates 23 and 25 and extends forwardly through the partition 13. Secured to the main shaft 25' is the sector 26 upon which is mounted, by means of the support 27 the springs 28 and 35 29, the purpose of which will be hereinafter described. Loosely mounted upon the shaft 25' is the plate 30 which supports the segment 31, this segment being concentric with the shaft 25'. The segment 31 is provided 40 with the stop 31' which extends inwardly and engages the slot 32 in the sector 26. A helical spring 32' is secured to the base plate 23 and to the shaft 25' and exerts a torsional pressure upon the sector 26, whereby the 45 abutment 33 of the sector 26 is held in engagement with the lug 31'. A lever 34 is mounted upon the rectangular portion 35 upon the shaft 25' and is secured thereto by the screw 36, the lever being disposed upon 50 the forward side of the partition 13. The segment 31 meshes with a pinion 37 which is mounted upon a shaft 38, this shaft being mounted in the plates 23 and 25. Disposed about the shaft 38 is the coiled spring 39, 55 and also upon said shaft is secured the ratchet wheel 40, which is engaged by the pawl 41, upon the gear wheel 42, which is loosely mounted upon the shaft 38. A spring 43 also mounted upon the gear wheel 60 42 engages the pawl 41, as shown in Fig. 2. The gear wheel 42 meshes with a pinion 44 upon the shaft 45, mounted in the plates 23 and 25. Also secured to the shaft 45 is the gear 46 which engages the escapement 65 mechanism 47. The escapement is rendered

adjustable by means of the adjustable weight 48, as is evident from the drawings.

Mounted upon the forward end of the shaft 45 is the break-wheel 49, which is insulated by the bushing 50. It will be noted 70 that the break-wheel acts mechanically only, no current passing through it. The spring 39 tends to cause a rotation of the shaft 38 in the direction of the arrow 51 which, by reason of the engagement between the ratchet mechanism and the gear 42 with the pinion 44 causes a rotation of the break-wheel 49 in the direction of the arrow 52. This mechanism for causing the rotation of the break-wheel is, as it has been described, normally 80 prevented from operation by reason of the engagement of the detent 53 upon the segment 31 with the supporting plate 25, as is indicated in Fig. 2.

Secured to the supporting plate 25 is the 85 support 54, to which are secured, by means of the screws 55-55, the contact springs 56, 57, 58 and 59, these contact springs being insulated from each other as shown. The spring 59 is so disposed that it may be controlled by the break-wheel 49 and so that it may, when engaged by the projections 60 upon the break-wheel, engage the contact spring 58. The spring 56 is adapted to be engaged by the pin 61 upon the segment 31, 95 the purpose of this engagement being hereinafter pointed out. The stop or pin 61 is so disposed that it may also be engaged by the spring 29 upon the proper operation of the sector 26, the purpose of this construction 100 being hereinafter described. The springs 56 and 57, the springs 58 and 59, and the springs 28 and 29 form, respectively, the pairs of contacts *a*, *b*, and *c* which are connected across the line limbs in multiple so 105 that the circuit may be closed by the operation of any one of the three pairs of contacts. The contacts are connected by means of conductors 62-62 to the binding posts 63-63 to which the terminals of the line 110 circuit may be secured.

The watchman or officer who is to make the reports of his beat by operating the substation apparatus is provided with a key which may be of such shape and size that it 115 may properly engage the extension 63' upon the shaft 38, this extension 63' being of such shape as to correspond with the construction of the key. The key is adapted to be inserted into the box through the aperture 64 which is disposed over the shaft 38, and it is evident that a clock-wise rotation of the key will wind the spring 39 and will cause a rotation of the segment 31 about the pivot shaft 25 in the direction 120 of the arrow 65. This will, by reason of the engagement between the lug 31 and the abutment 33 cause the rotation of the sector 26 and, consequently, of the lever arm 34. Upon the cover 2 I provide the stop 66, 130

which is so disposed that when the spring mechanism has been wound to such a degree that its release will cause one revolution of the break-wheel 49, the stop 66 will be engaged by the lever arm 34. When the key is withdrawn and the mechanism thereby released, the break-wheel 49 will make one complete revolution and will assume its normal position when the detent 53 engages the plate or frame 25. This rotation of the break-wheel will cause a circuit to be closed intermittently according to the code of the break-wheel consisting of the projections 60 by reason of their engagement with the contact spring 59, this engagement causing the electrical engagement between the springs 59 and 58. It will be noted at the central station that when the number of the substation is telegraphed but once it is to be considered a report by the watchman or officer of his beat.

When it is desired to send in to the central station a fire alarm the seal is broken, as has been heretofore described, and the box door is opened, thereby exposing to view the lever arm 34. When the lever arm 34 is depressed, thereby rotating the sector 26 about the shaft 25' in the direction of the arrow 65, the spring 29 will be brought into engagement with the stop 61 upon the segment 31 and will thereby be forced into electrical contact with the spring 28. The abutment 33' will then engage the lug 31' and will carry with it the segment 31. The contact will remain closed until the lever arm has gone to its limit, which is determined by the stop 67 upon the partition member 13.

When the lever arm 34 has been depressed to such an extent to wind the break-wheel mechanism sufficiently to cause, if it were released, three complete revolutions of the break-wheel 49, the stop 61 engages the spring 56 and brings it into electrical connection with the spring 57, thereby closing the circuit at this point also, this contact remaining closed as long as the stop 61 engages the arcuate end 57' of the spring 56. It is now evident that the circuit is closed during the entire downward stroke of the segment 31. This will cause a long dash at the telegraphic instrument at the central station and will indicate to the operator that the signal is a fire alarm. Upon the release of the lever 34 the spring 32' will cause the sector to rotate quickly about the shaft 25' in the direction of the arrow 70 until the abutment 33 engages the lug 31'. Thus the contact between the springs 28 and 29 is opened. The contact between the springs 56 and 57, however, will remain completed until the break-wheel 49 will have made one complete revolution. When the springs 56 and 57 part contact the long dash at the central station indicating a fire alarm will have been completed and the three following revolu-

tions of the break-wheel 49 will telegraph to the central station, three times repeated, the number of the substation. When the stop 53 engages the plate 25 the signal will have been completed and the central station will be informed as to what substation apparatus has been operated. It is evident from the foregoing that the watchman's signal and the fire alarm signal may be easily distinguished at the central station.

In order to secure against users who would not be careful to depress the lever 34 its entire distance, or persons who could not on account of the strength of the spring, the springs 28 and 29 are so disposed and the sector 26 is so constructed that the lever arm may be moved a predetermined distance depending upon the length of the slot 32 before the mechanism controlled by the main spring is affected. This movement of the lever arm would be sufficient to close the circuit for a short time at the springs 28 and 29. This will cause an unusual signal at the central station and it will indicate to the operator that an attempt has been made to operate some box in the circuit and an investigation can be made.

From the operation above described, it follows that, by providing a mechanism adapted when wound to operate signaling mechanism so that a characteristic signal would be transmitted four times unless prevented by coöperating means, and at the same time short-circuiting the signaling mechanism during the normal period required for the first sending of the signal, a characteristic indication may be made at the receiving station consisting in a dash upon the recording tape, the length of which indicates the duration of the closure of the circuit during the interval which would be otherwise occupied by the first sending of such signal. After the termination of this short-circuiting interval, such short circuit is opened and the signaling apparatus is effective to send the characteristic signal three times in succession. This affords the operator at the receiving station a positive indication other than the record of the signal itself that the signal thus sent indicates an alarm of fire instead of the record of a watchman's report. The distinguishing signal consisting in the long dash preceding the record of the fire alarm signal cannot be produced either by accident or design by the watchman in the course of his regular duties, but only by deliberately breaking the seal of the case and operating the lever 34. Thus, a positive means is employed for indicating the difference between the watchman's signal and a fire alarm signal.

It is evident from the foregoing that the construction may be made strong and durable and in no way needs a delicate adjustment to secure its proper operation. The

parts are such that they may be easily constructed and assembled and may easily be reached in case of necessity of repair.

It is evident that changes and modifications may be made within the spirit and scope of my invention by those skilled in the art, and I do not wish to be limited, therefore, to the precise construction herein shown.

10 I claim as new and desire to secure by Letters Patent:

1. In a device of the class described, the combination with a break-wheel, of spring mechanism for operating said break-wheel, 15 means for winding said break-wheel operating mechanism sufficiently to cause one complete revolution of the break-wheel, separate means for winding said break-wheel mechanism sufficiently to cause a plurality 20 of revolutions of the break-wheel, means associated with said separate winding mechanism for closing the circuit during part of the time while said break-wheel operating mechanism is being wound, and contact 25 springs associated with and adapted to be operated by said break-wheel whereby the circuit may be opened and closed.

2. In a device of the class described, the combination with a break-wheel, of spring 30 mechanism for operating said break-wheel, means for winding said break-wheel mechanism sufficiently to cause one complete revolution of the break-wheel, separate means for winding the break-wheel operating 35 mechanism sufficiently to cause a plurality of revolutions of said break-wheel, means associated with said separate winding mechanism for closing the circuit during the time of winding and means for closing 40 the circuit during part of the time of operation of the break-wheel.

3. In a device of the class described, the combination with a break-wheel, of spring

mechanism associated with said break-wheel for operating same, means for winding said break-wheel operating mechanism sufficiently to cause one revolution of said break-wheel upon the release of said mechanism, separate means for winding said break-wheel mechanism sufficiently to cause a plurality of revolutions of said break-wheel upon the release of said operating mechanism, means for closing the circuit during the winding of said operating mechanism, means for retaining the closed circuit during part of the operation of said break-wheel mechanism and contact springs associated with said break-wheel and adapted to be operated by the same.

4. In a device of the class described, the combination with a break-wheel, of spring mechanism for operating said break-wheel, means for normally preventing the operation of said mechanism, means for winding said mechanism sufficiently to cause, upon its release, one revolution of said break-wheel, separate winding mechanism for winding said operating mechanism sufficiently to cause, upon its release, a plurality of revolutions of said break-wheel, means associated with said separate winding mechanism for closing a circuit containing a telegraphic instrument during the winding of said break-wheel operating means by said separate winding mechanism, and means associated with said separate winding mechanism for retaining a closed circuit during part of the operation of said break-wheel mechanism upon its release.

In witness whereof, I hereunto subscribe my name this 5th day of May A. D., 1906.

GEORGE M. WILLIS.
